BAKER'S PEEL

Henry L. Schroeder, Chicago, Ill.

Application August 16, 1932. Serial No. 629,071

5 Claims. (Cl. 107—67)

The invention relates to a baker's peel and has for its primary object the provision of an improved peel which may be used by the baker of bread, crackers, etc. and which can be made largely of wood or other analogous fibrous material to meet the requirements of the individual baker.

Bakers' peels of the character to which my invention is adaptable are formed of elongated wood blades of various widths and lengths that are provided with handles by which they are manipulated in the handling of bread, crackers, etc., by bakers in connection with ovens and other requirements.

These peel blades may be made of integral wood strips suitably formed or they may be built up of a plurality of strips joined together somewhat like veneered wood is built up of separate relatively thin layers of wood glued together with a grain of the wood suitably arranged to counteract warping tendencies.

With the use of such peel blades made of wood or analogous material, the problem arises of providing a suitable attachable handle for operating the blade, which handle may be detached from one blade and used in connection with another since the handle parts frequently outlast many times the life of the blade which is subjected to the more intense heat likely to be found in the ovens.

An object of my invention is to provide an improved construction of peel blade and co-operating handle by which the handle may be rigidly secured in operative relation with the handle end of the blade in a manner to prevent loosening and also in the manner that will permit of ready adjustment in taking up any looseness that might develop between the handle and the blade portions of the device, which handle attaching structure is simple and economical to make and is not liable to be accidentally detached from the blade when in use.

Other objects of the invention will appear from the following description of the preferred embodiment thereof, which is hereinafter described with reference to the drawings, forming a part of the specification, the novel features being set forth in the appended claims.

In the said drawings:

Fig. 1 is a plan view of my improved bakers' peel with parts of the handle and blade portions broken away to decrease the length of the device in this view.

Fig. 2 is a side elevation of the device of Fig. 1.

Fig. 3 is a side elevation of a detached handle bracket, the latter being shown also in section in Fig. 4, which latter view is taken on the line 4—4

of Fig. 3, looking in the direction indicated by the arrows.

Fig. 5 is a broken cross sectional view taken on line 5—5 of Fig. 1 looking in the direction indicated by the arrows.

Fig. 6 is a broken transverse sectional view through the device of Fig. 1, the same being taken approximately on the line 6—6 of Fig. 5 looking in the direction indicated by the arrows.

Figs. 7 and 8 are broken vertical sectional views taken on lines 7—7 and 8—8, respectively, of Fig. 6, looking in the direction indicated by the arrows, illustrating details of the invention.

Figs. 9 and 10 are fragmentary sections taken respectively on lines 9—9 and 10—10 of Fig. 1, looking in the respective directions indicated by the arrows.

Fig. 11 is a broken detail sectional view showing the preferred construction of the end of my improved peel blade remote from the handle, and Fig. 12 is a view similar to Fig. 11, illustrating a modification of the construction shown in Fig. 11, and Fig. 13 is a modified form of the handle attaching portion of the structure.

In the broken view of Fig. 1, which is an elevation or a plan view of the complete device with handle attached as it would appear lying upon a flat surface, the blade portion of the peel, preferably, although not necessarily made of wood, is designated generally by the reference character 10 and the same, according to the conventional construction, will be made at the handle end of a suitable thickness for strengthening purposes so as to give the blade stability for the rugged use to which it is subjected frequently in connection with the heated ovens and the blade may be made of an integral piece of wood or of interleaved sections secured together by suitable means as casein or blood albumen glues, which are adhesives having admirable heat resisting qualities.

The blade 10 of any desired width for the specific purpose intended, will preferably, although not necessarily, be thinned toward the tip end which is opposite the handle engaging end as illustrated in the broken side elevation view, Fig. 2, and from which it will be seen that at the thick or handle end of the blade, it will have sufficient thickness to accommodate the handle attaching structure as described, which thickness ordinarily will run anywhere from three-quarters of an inch more or less to even greater thicknesses when the blades are considerably elongated and intended for the heaviest class of service. Then at this thickened or heel end of

- the blade, a longitudinally extending handle slot, the walls of which are designated by the reference character 11 in the sectional view Fig. 9, is cut in such a manner that intermediate the top 5 and bottom flat sides of the blade, adjacent to the slot 11, there will be an inner peripherally extending rib 12 beginning at substantially the point at the heel end of the blade where the slot 11 begins and extending thence inwardly into 10 the body of the blade to furnish a substantial seat several inches long for receiving the co-operating end of the peel blade handle, designated generally by the reference character 13 which will also preferably be formed of wood. 15 The hand engaging portion of the handle 13 may be round in cross section or it may be otherwise shaped to correspond somewhat to the end of the handle that is designed to enter the rabbeted blade slot 11, as indicated for example 20 in the cross sectional views, Figs. 5 and 9, where it is shown that the shaft 13 is cut to a size to fit snugly within the longitudinal handle opening 11, the same at the forward end and along the co-operating side edges being grooved as 25 indicated at 42 in the section views, Figs. 5 and 9, to co-operate with the tongue portions 12 of the slot and corresponding tongue portions 43 on the metallic handle brackets or clamps to be hereinafter described. The co-operating tongue 30 and grooved or rabbeted portions of the handle groove and the handle 13 will preferably be rounded to the general form of a semi-circumference at the forward end as indicated at 14, Fig. 1. This telescoping rabbeted connection between the handle and the blade assists in making 35 a firm connection between the handle of the blade which is assisted and re-enforced by a pair of specially constructed metallic brackets 15 secured to the sides of the handle member 13 by a plurality of screws 16 as shown in Figs. 1 and 40 6 to 8 inclusive. Opposing angular extensions on the brackets 15 are provided and extending below the same, as a part of the handle bracket structure and preferably integral therewith, are 45 flanges as designated at 17, Figs. 1, 3, 4 and 8, the lower extremities of which are slightly rounded, preferably as indicated in Fig. 3 to permit the same to enter the spaced pair of 50 opposing grooves extending on opposite sides of the handle slot in the heel end of the peel blade 10, midway between the face surfaces of the blade as designated by the reference character 18, Figs. 1 and 6 and 8.
- On opposite sides of the slot 11 and substantially evenly spaced therefrom, I bore a pair of round holes through the body of the blade as indicated at 19 extending between the opposite flat faces of the blade and a pair of bolt holes 55 are then drilled within the body of the blade at the heel end extending parallel to the handle slot from the grooves 18 on each side thereof and extending into and communicating with the bored openings 19. These last named holes are designed to take the longitudinally extending bolts 60 20 which are provided with heads 21 for supporting the bolts in the radially extending angular portions of the brackets 15 so that the threaded end of the bolts 20, as illustrated in Figs. 1 and 6 to 8 inclusive, may extend into the aforesaid circular openings 19 and engage and receive co-operating threaded nuts 22 so that when a suitable tool as a screw driver is applied to the bolts 20 and rotated, it will cause them to engage 65 the nuts 22 with a clamping action, the nuts 22 being held against rotation by reason of their 70 being preferably square in form and hence becoming embedded in the wood around the circular openings 19 when pressure is applied by the rotation of the screw bolts 20 which will also have the effect of drawing the rabbeted handle portion 13 within the tongue slot 11 and causing the opposing wedge portions 17 to engage within the slots 18 to more thoroughly clamp the handle in firm engagement with the blade. 75
- The described construction for joining the handle to the blade furnishes a permanent supporting means between these parts that effectively resist tendencies toward looseness or detachment under the most difficult conditions of heat in the presence of moisture and the like. 80
- Furthermore, an important feature of my improved peel is shown in Figs. 11 and 12 where the blade 10 is shown as thinned at the tip portion opposite the handle engaging end and frequently requires re-enforcement to increase the 85 length of life of the blade. 90
- In Fig. 10 I show the thinned tip end re-enforced by means of a pair of metallic strips 30 and 31 pressed into the material of the thinned wooden tip of the blade as illustrated in Fig. 11, each of these plates 30, 31, extending from side to side of the blade and secured thereto by some suitable heat resisting adhesive as a blood albumen glue which is found to be sufficiently tenacious 95 for this purpose. 100
- The re-enforcing plates 30, 31 may be formed as illustrated in the sectional view, Fig. 11, or as in the modified view, Fig. 12, where the plate 32, corresponding to the plate 30 in Fig. 11 is shown slightly elongated and the plate 33 corresponding to the plate 31 in Fig. 11 is shown considerably shortened so that the forward extremity of the plate 32 projects to provide a thin engaging metallic portion for the peel blade. 105
- In Fig. 13 I show a modified form of that part of the structure which functions to hold the handle member 13 in fixed position in the handle slot of the peel blade through the action of the screws 21 engaging the nuts 22 in the aforesaid holes 19 near the heel of the blade. In this view 110 the body of the handle shaft is shown in section and it will be seen that I utilize a pair of screw eyes 35, 36 in lieu of the brackets 15 and their attaching means heretofore described. The screw portions of these parts 35, 36 will preferably be 115 constructed like the threaded shanks of the ordinary wood screws as illustrated and I find that by using screws, the threaded portions of which will be regulated in length so as to reach a little beyond the longitudinal median line of the handle 120 shaft, a very effective interlocking action may be obtained at the overlapping forward extremities of the screws in the manner illustrated in Fig. 13 and from which it will be seen that when the screws 35, 36 are caused to enter the opposite 125 longitudinal side edges of the handle 13, usually after a hole is drilled through the shaft from side to side smaller in diameter than the average mean diameter of the screws in order that the peripheral threads thereon may engage the surrounding wood with a binding action, it will be 130 found when the points of the screws are brought into contacting relation, if the inserting rotation of the screws be continued, to cause their points to overlap in the manner illustrated in Fig. 13 135 by reason of the inherent shape at the pointed ends of the wood screws, the points upon engagement will tend to offset each other so that the points of the respective screws will tend to wedge 140 each other slightly apart as illustrated in sec- 145 150

tional view, Fig. 13, while the threads thereon will interlock at the contacting peripheries of the screws thus effectively locking these screws in position and preventing their being disengaged by 5 a direct outward pull on the eyes thereof which take the stove bolts 20.

When the modification illustrated in Fig. 13 is used, it will be apparent that the screweyes 35, 36 will be inserted in the handle to their respective positions illustrated in Fig. 13 before the handle is inserted in the slot 11 of the blade, then the bolts 20 may be inserted and their threaded ends passed into the spaced apart openings 19 at the heel end of the blade for engagement with the nuts 22 in the manner heretofore described.

In order that the invention might be understood the details of the preferred embodiment thereof have been illustrated and described but 20 it will be apparent that persons skilled in the art may resort to various modifications without departing from the purpose and spirit of the invention as defined by the claims.

I claim:

25 1. A peel comprising a blade having a slot extending inwardly from its heel edge and communicating between the flat sides of the blade, a handle member having a portion thereof disposed in said slot and substantially filling the slot co-operating, slidably, interlocking parts formed on the respective engaging portions of the handle member and the walls of the slot in the said blade, there being a pair of bolt holes extending into the body of the blade from the heel end thereof and being formed approximately 35 parallel with the said handle slot, means for drawing the said handle longitudinally into the said slot of the blade and for clamping the handle to the blade adjacent the heel end thereof, comprising a pair of laterally extending members secured on opposite sides of the handle shaft adjacent the portion thereof adapted to normally co-operate with the heel end of the blade, said members being provided with openings adapted 40 to receive headed bolts, and a pair of rotatable screw threaded clamping bolts engaging the said openings in the laterally extending members, and being adapted to engage the body portion of the blade in the said parallel bolt holes at the heel 45 end thereof.

50 2. A peel comprising a blade having a slot extending inwardly from its heel edge and reaching between the flat sides of the blade, a handle member for co-operating with the said slot in the heel end of the blade, there being co-operating tongue and groove portions formed upon the respective contiguous co-operating surfaces of the handle member and the peel body within the said slot to provide an interlocking engagement between the 55 handle member and the peel blade, and means for detachably clamping the handle member within the said slot at the heel end of the blade comprising a pair of oppositely extending eye brackets secured to the handle member and a pair of 60 rotatable metallic screw threaded members mounted in said eye brackets and engaged within the body of the peel blade at the adjacent heel end thereof.

65 3. A peel comprising a wooden blade having a handle slot disposed longitudinally thereof and extending inwardly from its heel edge and providing an opening between the two flat sides of the blade, a detachable handle member for the 70 peel blade in the form of a shaft having one end provided with means for interlocking, telescopic

engagement with the heel end of the blade within the said handle slot there being a pair of spaced apart openings extending through the body of the body of the peel blade from one flat side to the other flat side thereof on opposite sides of the aforesaid handle slots and within the body of the blade adjacent the heel end thereof, there being also a pair of substantially parallel communicating openings extending from the outer heel end of the blade between the flat sides thereof and communicating with the aforesaid openings within the body of the blade, a pair of clamping bolts, rotatably secured to the handle member and being adapted to pass through the aforesaid longitudinal openings to the aforesaid spaced apart openings extending between the flat sides of the blade, and means within the last said openings adapted to engage the aforesaid threaded bolts for adjustably clamping the said handle member to the heel end of the blade.

75 4. A peel comprising a blade having a handle slot disposed longitudinally thereof and extending inwardly from its heel edge and communicating between the two flat outer surfaces thereof, a handle member disposed in and substantially filling the slot in the blade, there being co-operating means between the said handle and the body of the blade within the said slot to permit a sliding engagement of the handle within the said slot, a pair of metallic brackets provided with bolt holes secured to opposite sides of the handle member, and a pair of threaded bolts rotatably mounted in the said bolt holes on the brackets and extending into the adjacent body of the peel blade at the heel end thereof, portions of the said bolts adapted to engage the body of the blade being screw threaded, and threaded metallic means embedded in the body of the blade for co-operating with the aforesaid threaded portions of the bolts whereby upon the rotation of said bolts the said handle may be adjustably and detachably secured within the said slot at the heel end of the blade.

80 5. A peel comprising a wooden blade having a rabbeted slot disposed longitudinally thereof, extending inwardly from its heel edge and communicating between the said flat surfaces of the blade, a grooved handle member disposed in and substantially filling the rabbeted slot of the blade, the grooved portions thereof extending on opposite sides of the handle beyond the portion thereof adapted to normally engage within the slot of the blade, there being also a pair of laterally extending grooves in the heel end of the blade on opposite sides of the aforesaid handle slot, a pair of angular metallic brackets adapted to be secured upon opposite sides of the said handle member to provide perforated angular portions adapted to receive rotatable clamping bolts, tongues formed integrally on the metallic brackets for engagement with the aforesaid grooves of the handle member, and other tongues formed integrally with the bracket for engagement with said grooves at the heel end of the blade, there being a pair of spaced apart openings in the body of the blade near the heel end extending from one flat side to the other flat side thereof, a pair of headed bolts rotatably mounted within the bolt holes within the aforesaid metallic bracket on the handle member, the said rotatable bolts being screw threaded at their inner extremities and extending through openings provided in the body of the peel blade between the heel end thereof and the aforesaid spaced apart openings extending between the flat sides of the blade, and metallic

threaded nuts engaging the aforesaid threaded ends of the rotatable bolts within the last said openings of the body of the blade, the said nuts being adapted to be embedded in the material forming the body of the blade when the said threaded bolts are rotated to exert a clamping

action between the foresaid metallic brackets of the handle and the body of the blade for detachably and securely clamping the handle to the blade.
